(57) **CLAIM**

The ornamental design for a wearable sensor adhesive patch as shown and described.

DESCRIPTION

FIG. 1 is a perspective view of a wearable sensor adhesive patch, showing our new design;

FIG. 2 is a front view of the wearable sensor adhesive patch; FIG. 3 is a rear view of the wearable sensor adhesive patch; FIG. 4 is a left side view of the wearable sensor adhesive patch;

FIG. 5 is a right side view of the wearable sensor adhesive patch;

FIG. 6 is a top view of the wearable sensor adhesive patch; and,

FIG. 7 is a bottom view of the wearable sensor adhesive patch.

The broken lines shown in the drawings illustrate portions of the wrist reader and form no part of the claimed design.
